UNITED STATES PATENT OFFICE.

FREDERICK WINSLOW, OF SWINDON, ENGLAND.

APPARATUS FOR TUNING AND ADJUSTING STRINGED FRETTED MUSICAL INSTRUMENTS.

Application filed June 23, 1927, Serial No. 200,795, and in Great Britain January 15, 1927.

This invention relates to apparatus for tuning and adjusting stringed fretted musical instruments.

With instruments having a graduated fingerboard, with frets, such as mandolins, guitars, banjos, lutes, balalaikas, ukuleles and kindred instruments, various intervals are imperfectly produced, and it is almost impossible to obtain the same note exactly in unison, from any closed (or stopped) and one open string on the same instrument. It is usual in most stringed fretted instruments, particularly with mandolins for them to go rapidly out of tune, and the strings having little tension and thus no brilliance, and the progression throughout the fingerboard is faulty, two identical notes on different strings not being resonant and neither true, with the open string, it being almost impossible to obtain true unison notes or octaves.

The object of this invention is to overcome these difficulties so that when the strings are stopped on a fretted instrument, they will give perfect diatonic and chromatic scales or intervals within such scales or chromatic scales throughout the fingerboard, also with two or more closed strings and one open string on the same instrument, the same note in perfect unison is produced.

It has been proposed to furnish each string with a separate string bearer, which is adjustable longitudinally of the string, in such a manner as to adjust the vibration length of the same, the string bearers also being adjusted vertically to the strings.

A device has also been proposed for varying the tension of the strings in stringed musical instruments, in which device, the strings near an end, were each passed underneath a pair of bridges, between which was arranged a screw-bolt having an eye, through which the string was threaded, by means of which bolt the string could be drawn upwards against the bridges and thereby tensioned.

In apparatus for tuning and adjusting, stringed fretted musical instruments in accordance with this invention are provided variably bevelled string bearings on nut and bridge, a tail piece, and diagonal stringing, the parts being disposed symmetrically about a centre-line through the instruments from head to tail piece, the nut, bridge and tail-piece being disposed at right angles to the said centre-line.

The bearings and spaces may have V-

shaped or otherwise suitably shaped ends to prevent forward or backward movement.

The bevels on the nut and bridge string bearers may be so made that the distance from the front of the bearing on the nut to the front-edge on the bearing on the bridge is the same for on each string or pair of strings.

The string bearers on the nut may be variably bevelled to give a different relation of each string to the frets on the fingerboard.

The anchor pins and guides in the tail piece of a mandolin for example may be such that each of the strings is the same length from anchor pin to machine string post.

The nut may have a rectangular base fitting into a corresponding groove in the instrument. The string spaces may be slotted and the string bearings staggered.

The accompanying drawings illustrate one form of the invention as applied for example to a mandolin.

In the drawings:—

Fig. 1 illustrates the application of the diagonal stringing from machines to tail piece.

Fig. 2 is a plan of the tail piece cover plate.

Fig. 3 is a front elevation of the tail piece.

Fig. 4 is a plan of the nut.

Fig. 5 is a front elevation of the bridge.

Fig. 6 is a plan of the bridge.

Fig. 7 is a similar view to Fig. 4, but with the strings removed.

Fig. 8 is a sectional elevation taken on line Q—Q of Fig. 7.

Figs. 9, 10, and 11 are sectional elevations taken on lines R—R, S—S and T—T, respectively of Fig. 7, but showing the nut only.

Fig. 12 is a plan view of the bridge string bearer and spacer.

Figs. 13, 14, 15 and 16 are sectional elevations taken on lines U—U, V—V, W—W, and X—X respectively of Fig. 12.

Fig. 17 is a sectional elevation taken on line Y—Y of Fig. 2, and

Fig. 18 is a sectional plan taken on line Z—Z of Fig. 17.

In the drawings I provide variably bevelled string bearings 1^a and 1^b on both the nut 1^a and bridge 1^c together with a tail-piece 1^d and a system of diagonal stringing. Everything must be disposed on a centre line α — α throughout the instrument from head to tail-piece. The nut 1^a, bridge 1^c and tail-piece 1^d must be at right angles to the centre line, and all parts must be symmetrically disposed, about the centre line that is to say.

above and below the centre line X—X in Fig. 1 in the example illustrated.

The variably bevelled bearing 1^b and slotted spacer 2^b on the bridge 1^c are fitted with 5 V shaped ends 2^d to prevent their movement forward or backward, while the bearing 1^b and spacer 2^b can be adjusted in the vertical plane, for adjusting the height of the strings 2^c. The height of the bearing on the bridge 10 is such that the clearance of the string at the twelfth fret is one sixteenth part of an inch.

The string bearers 1^a in the nut 1^a, are variably bevelled to give a different relation of 15 each string G, D, E, A to the frets 2^c on the fingerboard 2^c. The strings are held in position on their bearings 1^a by a slotted spacer 2^a at the rear of the nut, which retains them in their correct longitudinal position. The 20 height of the bearing of the nut 1^a is the same as the height of the frets 2^c above the fingerboard. The position of the nut 1^a on a mandolin fingerboard, is such, that from the front edge of the bearing of the strings E giving 25 note E on the nut, to the twelfth fret is exactly one half of the length of the vibrating string length in use. In this case as the length of thirteen and a quarter inches is used, the distance is six and five eighths 30 inches. The string E is thus given the setting which is usual, but the other strings are differently disposed by the bevels, these variable bevels together with corresponding bevels on the bridge (described later) successfully overcome any sharpening or flattening 35 of notes when playing far up the fingerboard.

The disposition of the anchor pins 3 and guides 4 in the tail-piece 1^d and the tuning pins 5 is such, that each of the eight strings 40 of a mandolin is the same length from anchor pin 3, to tuning post 5.

The diagonal stringing 5^a, 5^b provided to retain the bridge in a central position, and increase the tension on the strings, which 45 means brilliancy of tone. The strings are thus held rigidly in place, preventing any alteration of pitch (musical note) and ensuring the equalizing of the length of all strings. The nut has a rectangular base 5^c fitting a 50 corresponding groove 17 in the neck of the instrument at the end of the fingerboard. The bridge string bearings 1^b and spacer 2^b (made in one unit) have V-shaped ends, the string bearings 1^a and 1^b on the nut and bridge 55 are staggered, variably bevelled or zig-zagged as at 5^e, 5^f, 5^g, 5^h, 5ⁱ, 5^m, 5ⁿ. The vibrating length of each string, between its bearings is the same. The string spacers 2^a and 2^b are slotted as at 5^o and each slot at the back 5^o of spacer finishes with a radius on the side the string makes an angle. The tail-piece with anchor pins 3 and guides 4 is so disposed that the length of each string from another pin 3 to tuning post 5 is the same, the diagonal 60 stringing retaining the bridge in a central 65

position. Transversely a slot 6 is cut in the top of the centre of the nut 1^a for separating the string spacers 2^a from the string bearers 1^a. The back corner 6^a of the string spacer is bevelled; on plan, the necessary slots 5° 70 are cut in the string spacer 2^a, to receive the eight strings of a mandolin to a depth, sufficient for each string to make its bearing on the string bearer 1^a. Each slot at the back of the spacer 2^a finishes with a rounded off portion on the side that the string makes an angle towards the tuning post 5. String bearers 1^a are staggered in relation to each other for the four pairs of strings. The width of each bearer string seating is similar to the 75 frets. The front edges of the bearings for the strings G, A, giving notes G and A are flush with the end of the fingerboard. The rear edges of the bearings for the strings G, A, are bevelled to the bottom of the slot 6 dividing the string bearer 1^a and string spacer 2^a. The bearing for the D string giving note D is approximately in the centre of the string bearer 1^a, having a bevel on the front and rear of the string bearer 1^a. The bearing for the E string has its back edge adjoining the slot 6 between the string bearer 1^a and spacer 2^a the front edge of the bearing for the E string being bevelled.

The bridge 1^c is made from wood or fibre and its base is curved to coincide with the soundboard 7^b. Transversely on the underside a recess 7 is cut across in the centre, providing two bearings to the soundboard. Rising to the top of the bridge 1^c the thickness is reduced. Three holes 8 with bell 8^a mouths on each side are made horizontally through the thickness of the bridge, to allow free transmission of vibration from string to soundboard. The top of the bridge 1^c is recessed and each end of the recess is V shaped as at 8^b for receiving the string spacer 2^b and bearer 1^b. The string spacer 2^b and bearer 1^b are made in one unit, from pearl or some other hard substance fitting the recess 8^c in the bridge. The front and back are vertical and the ends are V shaped as at 2^d to fit the ends of the recess 8^c in the top of the bridge. The string spacer 2^b is separated from the string bearer 1^b by a slot 9. The string spacer 2^b is the rear raised portion, the back corner of which is bevelled, the necessary slots 10 are cut in the string spacer 2^b, to receive the eight strings of the mandolin, to a depth sufficient for each string to make its bearing on the string bearer 1^b and each slot at the back of the spacer 2^b finishes with a radius on the side that the string makes an angle towards the tail-piece. String bearers 1^b are cut away below the level of the spaces 2^b and are staggered in relation to each other for the four pairs of strings. The width of each bearer string seating 1^b is similar to the width of the frets. The front edges for the strings G, A, are bevelled half-way across 125 130 135

the bearer 1^b. The back edges of the bearings of the strings G, A, are formed by the dividing slot 9 between spacer 2^b and bearer 1^b. The bearing for the string D is approximately in the centre of the string bearer 1^b having a bevel on the front and rear of the string bearer 1^b. The bearing for the E string E has its back edge bevelled towards the dividing slot 9 leaving the seating for the string E on the front portion of the bearer 1^b. It will thus be seen that the bevels on the nut and bridge string bearers 1^a and 1^b are so cut that the distance from the edge of the bearing 1^a on the nut 1^a to the front edge of the bearing 1^b on the bridge 1^c is exactly the same on each pair of strings. The tail-piece 1^d is made from thin sheet metal. The two sides 11 are flanged and parallel to the outside strings, the flanges 12 tapering towards the soundboard 7^b, the bottom flange 14 being the same depth as the sides, forming a box for the anchor pins 3 and guides 4. The top flange 15 turns outwards for resting on the soundboard. Anchors 3 and guides 4 for the strings are circular with enlarged semi-circular or snap heads and are riveted to the back portion of the tail-piece.

The disposition of the anchor pins 3 and guides 4 is such, that each of the eight strings of a mandolin is the same length from anchor pin 3 to tuning post 5. On the left of the vertical centre line of the tail-piece are at the top two anchor pins E³ for the strings E, these strings taking an angular direction to the bridge 1^c and parallel to each other; and thence over the nut 1^a. Below the anchor pins for the strings E and on the left of the vertical centre line of the tail-piece, are the two guides A⁴ and anchor pins A³ for the strings A. These strings from the guides A⁴ run parallel to each other and at an angle to the bridge 1^c and thence over the nut. On the right of the vertical centre line of the tail-piece are at the top, two anchor pins G³ pins for the strings G, these strings taking an angular direction to the bridge 1^c and parallel to each other, thence over the nut of the machine head. Below the anchor G³ for the string G and on the right of the vertical centre line of the tail-piece, are two guides D⁴ run parallel to each other and at an angle to the bridge, thence over the nut.

Over the tail-piece is a push-on flanged cover plate 16 with top flanged plate and tortoiseshell covering over the strings.

The angle of the strings 2^c, being increased by their diagonal disposition provides a firmer grip on the nut 1^a and bridge 1^c and at the same time prevents any slackening of the strings and consequent alteration of pitch; also, at the same time the bridge 1^c, is held in its correct position thereby, making the strings more responsive in action. With usual stringing, as heretofore adopted, there

is more tendency for the bridge 1^c to move both transversely and longitudinally which, of course, disarranges the whole setting of the strings with the result that true notes cannot be obtained. The pairs of strings 2^c on a mandolin, for instance, are of different gauge and were these in the same relation to the frets throughout, when notes were stopped on one pair they would not be in exact resonance or unison with the same note stopped on another pair. It is usual for these to have straight bearers, that is continuous, or all in the same distance relation to the frets. To correct these false notes each pair of strings is provided with a different distance relation to the frets by staggering the bearings 1^a, 1^b for each pair of strings.

In order to retain the same length of vibrating strings, the distance between the bearers 1^a, 1^b for each pair of strings is kept the same, but each pair has a different distance relation (i. e., the measurement from the front of the bearing to any fret is not the same for all strings) to the frets on the finger-board.

If a note be stopped with a straight bearing 90 throughout, it may be either higher or lower than the correct pitch required and not the same as the same note on another pair of strings. According to this invention this bearing is altered to a staggered bearing so 95 as to move the bearing for each pair of strings forward or backward, thus the pair of strings is stopped at a different distance from the bridge or nut until correct.

What I claim and desire to secure by Letters Patent is:—

1. Apparatus for tuning and adjusting stringed fretted musical instruments comprising in combination variably bevelled string bearings on nut and bridge, a tail piece, and diagonal stringing, the parts being disposed symmetrically about a centre-line through the instrument from head to tail piece, the nut, bridge and tail-piece being disposed at right angles to the said centre-line. 105

2. Apparatus for tuning and adjusting stringed fretted musical instrument comprising in combination variably bevelled string bearings on nut and bridge, a tail piece, and diagonal stringing, the parts being disposed symmetrically about a centre-line through the instrument from head to tail-piece, the nut, bridge and tail-piece being disposed at right angles to the said centre-line and shaped ends on the bridge to prevent movement 120 lengthwise of the instrument.

3. Apparatus for tuning and adjusting stringed fretted musical instruments comprising in combination variably bevelled stringed bearings on nut and bridge, a tail piece, and diagonal stringing, the parts being disposed symmetrically about a centre-line through the instrument from head to tail piece, the nut, bridge and tail-piece being disposed at right angles to the said centre-line, string bearers 130

being so made that the distance from the front of the bearing on the nut to the front edge of the bearing on the bridge is the same for each string or pair of strings.

5. 4. Apparatus for tuning and adjusting stringed fretted musical instruments comprising in combination variably bevelled string bearings on nut and bridge, a tail piece, and diagonal stringing, the parts being disposed 10 symmetrially about a centre-line through the instrument from head to tail-piece, the nut, bridge and tail-piece being disposed at right angles to the said centre-line and the nut having and the string bearers on the nut being variably bevelled to give a different relation of 15 each string to the frets on the fingerboard.
5. Apparatus for tuning and adjusting stringed fretted musical instruments comprising in combination variably bevelled 20 string bearings on nut and bridge, a tail piece, and diagonal stringing, the parts disposed

symmetrically about a centre-line through the instrument from head to tail-piece, the nut, bridge and tail piece being disposed at right angles to the said centre-line and the nut having a rectangular base fitting into a corresponding groove in the instrument, the string spacers being slotted and the string bearings staggered.

6. In a mandolin, variably bevelled string 30 bearings on nut and bridge, a tail piece, and diagonal stringing, the parts being disposed symmetrically about a centre-line through the instrument from head to tail piece, the nut, bridge and tail piece being disposed at right 35 angles to the said centre-line and the anchor pins and guides in the tail-piece being such that each of the strings is the same length from anchor pin to machine string post.

In testimony whereof, I affix my signature.

FREDERICK WINSLOW
